UNITED STATES PATENT OFFICE.

WILLIAM CHESTER CUSHING, OF TULSA, OKLAHOMA.

OIL LIFT.

1,402,218.

Specification of Letters Patent.

Patented Jan. 3, 1922.

Application filed March 17, 1920. Serial No. 366,627.

To all whom it may concern:

Be it known that I, WILLIAM CHESTER CUSHING, a citizen of the United States, and a resident of Tulsa, in the county of Tulsa 5 and State of Oklahoma, have invented certain new and useful Improvements in Oil Lifts, of which the following is a specification.

This invention relates generally to oil lifts, and more particularly to an improved automatic inlet and discharge valve for oil lifts of the swab type.

The primary object of the present invention is to provide an improved automatic valve of this character which will not only permit the free flow of the oil from below to above the swab on the down stroke but which will also permit free flow from above to below the swab on the upstroke of all 20 oil above exceeding the capacity of the lift while automatically cutting off the flow and retaining all of the oil thereabove within the capacity of the lift.

Another object is to provide an improved 25 valve of this character which is adjustable to meet the various requirements of different lifts and which is of strong and durable construction, highly reliable and durable in operation, and easy to manufacture.

Other objects and advantages reside in the 30 certain novel features of the construction, arrangement and combination of parts and will become apparent as the description proceeds reference being had to the accompanying drawings forming part of the specification and in which:

Figure 1 is a side elevational view of my 35 improved valve applied, the well casing being shown in section;

Figure 2 is a vertical sectional view through 40 my improved valve, the parts being in position taken on the down-stroke of the swab;

Figure 3 is a fragmentary view in vertical 45 section of my improved valve, showing the parts in position to discharge the oil in excess of the capacity of the lift;

Figure 4 is a detail view in top plan of the 50 discharge valve;

Figure 5 is a top plan view of the valve 55 casing;

Figure 6 is a bottom plan view of the valve 60 casing;

Figure 7 is a side elevational view of the locking plug;

Figure 8 is a side elevational view of the locking pin; and

Figure 9 is a detail view of a modified form of discharge valve head and seat.

Referring to the drawings, the numeral 10 designates a section of the well casing in 60 which the swab indicated generally at 11 is adapted to reciprocate, the reciprocatory motion being imparted to the swab by virtue of its connection to the lower end of a string of tools 12. The swab consists as usual of upper and lower flanges 13 and 14, respectively, and a rubber 15 disposed between the flanges. The upper flange has a hollow neck portion 16 provided with an outlet 17 and a connecting head 18. A suitable tube (not shown) 70 extends between the flanges and affords a passage through the swab as in the conventional construction. A collar 19 is threaded onto the lower end of this tube as in the conventional swab and to this collar 19 is secured a coupling member 20 which has a coacting nipple 21 adapted for threaded engagement with the upper internally threaded end of the valve casing to be hereinafter more fully described.

The valve casing 23 is preferably of hollow cylindrical form, and has its upper portion thickened, as at 24, and contracted to form a neck 25 internally threaded for engagement with the nipple 21. The thickened 85 portion 24 is machined or ground to provide a valve seat 26. The lower end of the valve casing 23 is internally threaded, as shown in the drawings, and receives an apertured plug 27 constituting an abutment. The plug 27 is 90 preferably provided with a plurality of circularly arranged apertures 28 and a large central aperture 29. It is thus seen that there is a passage provided affording of itself free flow of the oil through the swab.

A discharge valve 30 cooperates with the seat 26 of the valve casing. This discharge valve is formed with a central opening 31 therethrough and a depending skirt 32 is formed integral with the valve and surrounds this opening. The upper face of the valve adjacent this opening is formed with a valve seat 34. A coil spring 33, preferably of relatively heavy structure, has its lower end resting against the abutment 27 and has 105 its upper end bearing against the under side of the valve 30. This coil spring tends to maintain the discharge valve 30 normally

closed. The pressure operated inlet valve 34 controls the flow through the opening 31 of the discharge valve. This valve 34 has a depending stem 35 which is received in the 5 valve guide 36 consisting of an apertured hub 37 and spider arms 38 preferably formed integral with the skirt 32 of the discharge valve 30. The lower end of the valve stem is threaded to receive a head 39 prefer- 10 ably in the form of a hexagonal nut.

The head 39 may be locked to the valve stem by a locking pin 40, shown in detail in Figure 8, and the abutment 27 may be locked in adjusted position by the locking plug 41, 15 shown in detail in Figure 7.

In operation, the coil spring 33 having been set to the proper tension by adjustment of the abutment 27, the abutment 27 is locked in position by the insertion of a locking plug 41, as shown in Figure 2. The valve casing is then secured to the swab by adjustment of the nipple 21 thereof and the swab is then lowered in the well. On the down-stroke of the swab the pressure of the 20 oil moves the inlet valve 34 to the position shown in Figure 2, permitting the oil to flow freely upwardly through the swab to above the same. On the up-stroke of the swab, if the oil which has been admitted to above 25 the swab exceeds the capacity of the lift, the degree of resistance unseats the discharge valve 30 and permits flow of oil past the same to below the swab. The discharge valve remains unseated as long as the oil 30 above the swab exceeds the capacity of the lift. When sufficient oil has passed from above to below the lift to reduce the quantity 35 above to within the capacity of the same, the coil spring 33 seats the discharge valve 30 and as the inlet valve 34 is also seated by the pressure further flow is prevented and the oil above the swab is lifted. It is obvious that the great range of adjustment necessary to meet the various requirements 40 of different lifts may be readily attained by the adjustment of the abutment 27. Moreover, the valve casing occupies the same position and practically the same amount of 45 space as the check valve casing now in use.

and affords no obstruction nor bulk likely 50 to interfere with the proper operation of the swab.

It is to be understood that by the term oil in this specification is included all of the fluids that are to be found and contended 55 with in oil wells, such as water, gas, etc., as well as the hydrocarbons on oil proper.

The head of the discharge valve 30 and its seat 26 may be constructed in the form shown in Figure 9, the feature of the construction 60 residing in the ball surface.

I claim:

In an oil lift of the character described, the combination with a swab having a passage therethrough, of a cylindrical valve 65 casing having its ends open and communicating one with the swab passage and the other to below the swab, said valve casing having a thickened portion at its upper end and provided with a valve seat, an annular 70 discharge valve of a diameter less than the internal diameter of said casing cooperating with said valve seat and having an opening therethrough, said discharge valve being provided on its upper side and around said 75 opening with a valve seat and having a cylindrical skirt co-axial with the cylindrical casing depending from around the lower side of said opening, a pressure operated disk valve co-operating with the valve seat of said annular valve and having a depending stem extending axially of the skirt of the discharge valve, guiding means for said disk valve including an apertured hub 80 receiving the stem and spider arms integral 85 with the skirt, and a coil spring disposed in the cylindrical casing adjacent the inner wall thereof and embracing the skirt of the discharge valve to be confined between the skirt and the casing and bearing against the 90 under side of the discharge valve to thereby urge said discharge valve to its seat and constrain said discharge valve to substantially 95 rectilinear movement and said spring to its proper field of action, all as and for the purposes set forth.

WILLIAM CHESTER CUSHING.
